UNITED STATES PATENT OFFICE.

JOHN B. OWENS, OF METUCHEN, NEW JERSEY.

KILN-CAR.

1,321,388.

Specification of Letters Patent. Patented Nov. 11, 1919.

Application filed August 17, 1918. Serial No. 250,322.

To all whom it may concern:

Be it known that I, JOHN B. OWENS, a citizen of the United States, residing at Metuchen, in the county of Middlesex and State of New Jersey, have invented certain new and useful Improvements in Kiln-Cars, of which the following is a specification.

This invention relates to cars which are used in tunnel kilns for conveying the clay products or wares to be fired.

Kiln cars are entered in the tunnel, one at a time, finally making up a train which completely fills the tunnel, the successive cars pushing those in advance. Suitable mechanism is employed to push the cars into and through the tunnel. Each car, including the one at the extreme head end of the train, is directly engaged by the next car thereafter, the entire train being pushed, as a unit, through the tunnel.

Cars used in tunnel kilns are sometimes a little distorted in shape due to imperfect manufacture, or, to the very high temperature to which they are subject in the kiln. Should one or more cars be a little twisted from such causes and consequently not squarely engage where they contact with each other, or, engage at the corner of the car, instead of at the central portion of the end thereof, the corner of the car will be broken off, or, the car forced out of alignment with the other cars by reason of the force necessary to move the train of cars in the kiln.

Kiln cars are subject, as at present constructed, to passage of air from below the cars to the space above them, and, also, to heat passing down from above the cars to the space below them, thus destroying the seal which should be maintained between the section of high temperature above the cars, where the clay products and ware are being fired, and the section of the tunnel where the running gear of the cars travels, which should be kept cool to avoid injury to the running gear. Attempts heretofore made to maintain the integrity of the seal between the ends of the cars and prevent the aforesaid air and heat leakage have not been successful, so far as I am aware.

The object of my invention is the provision, first, of improvements whereby the car ends engage only at the center, even

though the car be of imperfect construction or has become warped from the heat in the tunnel; second, improvements whereby the car ends become automatically sealed, when engaged, thereby preventing the passage of air upwardly, or heat downwardly, between the ends of the cars, and which, furthermore are adapted to have a clay wad, asbestos rope, or the like, applied to perfect said seal.

These objects are attained by the provision, first, of a novel bumper at one end of the car, adapted to engage the center of the end of the car in advance so that the pushing pressure is applied only at the center of each car; second, of novel tongue and groove ends on the car, whereby the grooves on one car receive the tongues on the adjoining car to effect a seal between the car ends, which may be perfected by the use of a clay wad, asbestos rope, or the like; third, of the bumper and sealing construction in conjunction with each other.

A further object of the invention is the provision of a kiln car which has grooved side sills adapted for the reception, and anchoring, of fire brick or fire clay should it become necessary to protect the side sills from the heat.

My kiln car may be of cast iron, or, of channel iron riveted together.

In the accompanying drawings: 85

Figure 1 is a plan view;

Fig. 2, a side elevation;

Fig. 3, an end elevation;

Fig. 4, a detail section on line 4—4, Fig. 1;

Fig. 5, a similar view on line 5—5, Fig. 1; 90

Fig. 6, a detail plan view, partly in section, showing the ends of two cars engaged;

Fig. 7, an enlarged detail section on line

7—7, Fig. 6, and Figs. 8 and 9, details of

modified seals for the car ends. 95

The car 1 which is of cast iron, integral throughout, is preferably provided with a rim or flange 2 extending upwardly from its top along its four sides to retain slabs 2^a of fire clay, Fig. 4, which constitute its fire-proof platform or deck on which the clay products or saggars are supported. 100

The side sills 3 have grooves 4 adapted to receive fire brick or fire clay 3^a, Fig. 4, should it become necessary to protect the 105 sides of the car from the heat. These

grooves will anchor and retain firebrick or fire clay, being made of sufficient depth for that purpose.

At one end of the car are two horizontal tongues 5 which are separated at their inner ends by a space 6, leaving an exposed surface 7 in line with the longitudinal axis of the car. The tongues are preferably rounded at their outer edges 8 and are 10 tapered from their bases to their ridges in cross-sectional form, as shown in Figs. 5 and 7.

At the other end of the car are two horizontal grooves 9 which are slightly deeper 15 than the extent of projection of the tongues 5 from the other end sill of the car. The grooves 9 are adapted to receive the tongues 5 on the adjoining car to seal the joint between the car ends and thus prevent air 20 from passing upwardly from below and heat from passing downwardly from above the cars between the ends of the latter. This seal is automatically established when the cars come together. The seal may be perfected by laying a clay wad, asbestos rope, or a like, 5^a on the tongues 5, prior to engagement of the cars, so that said wad will be mashed and otherwise conform to the joint established between the car ends, as 30 shown in Fig. 7.

Projecting a very small distance, in practice about one-eighth of an inch (although I do not confine myself to that dimension), from that end of the car having the grooves 35 9, is a center bumper 10 which is adapted to engage the surface 7 of the adjoining car when the cars come together. The slight projection of this bumper beyond the car end provides for the holding apart of the 40 end sills of the cars on either side of the center a distance of about one-eighth of an inch and results in the pushing pressure being applied solely at the center of the end sill of a car. The bumper prevents the cars 45 from being thrown out of alignment should they be distorted from imperfect construction, or, from the heat of the kiln.

The wheels 11 may be mounted, as by 50 roller bearings 12, on short independent axles 13 secured to hangers 14, integral with the car 1, by screws, or other fastening means 15. Clearance is thus obtained beneath the car, which cannot be had when full-length axles are used.

55 While I have illustrated the tongue and groove seal as being provided on the cast iron car 1, the tongue and groove may, instead, be provided on the ends of the fire-

proof platform or deck 2^a, as shown in Fig. 8 at 15, with an interposed head-resisting 60 wad 5^a.

Sealing of the car ends may be effected, in another modification, by the provision of horizontally arranged upper and lower, parallel angle-plates, or the like, secured to 65 one car end and defining a groove adapted to receive the end of the next car, as shown in Fig. 9 at 16, with an interposed head-resisting wad 5^a.

The foregoing modifications are intended 70 to be covered by the claims.

What I claim is:

1. A kiln car having horizontal grooves at one end, with an intervening bumper at the center of the car end, and horizontal 75 tongues at its other end, with an intervening contact surface, said grooves being adapted to receive tongues on the end of another kiln car, said tongues being adapted to project into grooves on the end of another kiln 80 car, and said bumper and contact surface being adapted, respectively, to engage their corresponding mating parts on another kiln car, whereby the spaces between adjoining cars may be sealed and the pressure of one 85 car on another will be applied to the centers of the ends thereof, said grooves and tongues being adapted to be sealed by an interposed heat-resisting material.

2. A kiln car having a one piece frame 90 provided with an integral projecting pushing bumper at the center of one end to engage the center of the end of a corresponding kiln car.

3. A kiln car having grooves at one end, 95 tongues at its other end corresponding to the grooves, and a projecting pushing bumper at its grooved end.

4. A kiln car having a pair of horizontal grooves at one end, a pair of corresponding 100 tongues at its other end, said parts being adapted to be sealed by an interposed heat-resisting material, and means whereby one car may be pushed by another car while maintaining the car ends of adjoining cars 105 in slightly separated relationship.

5. A kiln car having side sills provided with longitudinal grooves, and heat-resisting material contained within said grooves.

6. A kiln car having a one-piece frame 110 whose side sills are provided with longitudinal grooves, and heat-resisting material contained within said grooves.

In testimony whereof I affix my signature.

JOHN B. OWENS.
